UNITED STATES PATENT OFFICE.

WILLIAM C. CARR, OF BUFFALO, NEW YORK.

CAR FOR TRANSPORTING ORE OR OTHER MATERIAL.

941,405.

Specification of Letters Patent. Patented Nov. 30, 1909.

Application filed December 11, 1908. Serial No. 466,999.

To all whom it may concern:

Be it known that I, WILLIAM C. CARR, a citizen of the United States, residing at Buffalo, in the county of Erie and State of New York, have invented new and useful Improvements in Cars for Transporting Ore or other Material, of which the following is a specification.

This invention relates to an improved car which is chiefly adapted for transporting ore or other material and the objects of the invention are to simplify the construction of cars of this class and to provide a strong and durable structure.

The invention also relates to certain details of construction which will be herein-after described and claimed, reference being had to the accompanying drawings in which an adaptation of the invention is shown.

Figure 1 is a side elevation of the improved car with one end thereof shown in section to disclose the construction. Fig. 2 is an enlarged detached side view of a fragment of the door carrying the locking bolt. Fig. 3 is an enlarged detached central section through the connecting rod which couples the bell crank and the lever for releasing the doors. Fig. 4 is an end view of the improved car looking in the direction of the arrow V, Fig. 1. Fig. 5 is a vertical transverse section through the car on line *a a*, Fig. 1. Fig. 6 is a vertical transverse section through the car body and frame on line *b b*, Fig. 1, showing the doors open to discharge the load. Fig. 7 is an enlarged fragmentary section through the doors on line *c c*, Fig. 1, showing the locking device for locking the doors when closed.

In referring to the accompanying drawings in detail, like numerals designate like parts.

The car body is composed of two sides 1 and 2, two ends 3 and 4, a bottom in two sections 5 and 6, hinged oppositely to each other to the sides. The sides incline toward each other from the top downward and the ends also incline toward each other from the top downward thereby forming a tapering body, the interior of which gradually reduces in size from the top toward the bottom. The lower portions of the ends extend below the sides and have their lower edges inclined toward each other at a greater angle from the vertical than the side edges of the upper portions of the ends, and said

edges of the lower portion of each end meet at a central point or apex which forms the lowest depending point. The bottom sections 5 and 6 are hinged to the lower margin of the sides by strap hinges 7, preferably three in number, and in opening swing transversely from each other from the position shown in Fig. 5 to the position shown in Fig. 6. The sections 5 and 6, when closed, have their inner longitudinal edges locked together and the upper surface of the side margins of their ends fitted against the edges of the lower depending portions of the ends of the car body, as shown in Fig. 5.

The car body is supported within a rectangular frame which consists of two longitudinal side members 8, two transverse end members 9 which connect the ends of the side members, and two sets of supplementary frame members, each set of which consists of two transversely arranged members 10 and 11. These supplemental frame members 10 and 11 are riveted to the rectangular frame near its end and are separated sufficiently to permit the bolting thereto of separated projecting brackets 12 which extend diagonally upward from a casing or housing 13 inclosing an electric motor.

The shaft 14 of each motor constitutes one of the car axles and has car wheels 15 attached to its ends.

To lessen the friction, an anti-friction bearing, preferably a roller or ball bearing, is fitted around each projecting end of the said shaft 14, between the casing 13 and the car wheel 15 and is mounted in an inclosing support 16 which is bolted directly to the side of the casing. In this way each car axle is supported from the car body by the motor casing 13 itself, dispensing with all separate brackets, and a very wide bearing is also provided owing to the oppositely located anti-friction bearings.

A dished or flanged plate 17 is bolted to the bottom of each motor casing 13 and brackets 18 are bolted to the opposite sides of the plate in which vertical current conducting brushes 19 are yieldingly mounted.

The brushes are located vertically beneath the car wheels 15, see Fig. 1, and are adapted to take the current from the under-surface of the rails on which the wheels travel.

Means are provided for locking the sections of the bottom in closed position which preferably consist of a locking bar 20 which is slidably mounted in a metal supporting

plate 21 fastened to the inner margin of one of the sections and has lateral hooks 22 arranged at intervals, and metal strips 23 riveted to the inner margin of the other section of the bottom which fit in slots 24, in the first mentioned section when the sections are closed and have projecting loop ends 25 in which the hooks 22 engage to lock the two members together.

10 Four strips 23 are utilized in the adaptation shown in the accompanying drawings and a like number of hooks 22 are also formed on the locking bar 20 so that the sections are secured together very strongly.

15 The locking bar is retracted to release the sections by mechanism which is preferably operated by stationary means located in the vicinity of the track on which the car travels and strikes or impinges against a part of 20 said mechanism as the car passes.

A double crank which is pivotally mounted at an intermediate point on a pivot 26 extending from a plate 27 bolted to one of the sections of the bottom, has its lower end 28 projecting between two lugs 29 and 30, extending upward from the locking bar 20 and its upper end universally jointed to one end of a connection.

25 A bell crank 31 has one of its members 30 universally jointed to the opposite end of the connection and its other member provided with a roller 32. The connection between the bell crank and the double crank is required to be of universal character to 35 allow for the opening and closing of the sections of the bottom and is preferably formed substantially as shown in Fig. 3, which consists of a screw threaded bar and two tubular socket members fitted on the 40 ends of the bar.

The bar comprises an enlarged central portion 33 having a knurled or roughened surface and two screw threaded end portions 34 and 35 which are threaded oppositely to 45 each other.

The socket members 36 and 37 are each shaped to form one element of a universal ball joint and are provided with side openings 38 and 39 through which the ball ends 50 40 and 41 of the double crank and the bell crank are fitted into said sockets to form the other elements of the universal joints.

55 The doors 5 and 6 are limited in their opening movement by stops arranged as shown in Figs. 1 and 6, and consisting of angular bars 42 bolted to the side frame members 8 and depending therefrom. These stops 42 are arranged so that the doors 5 and 6 when open, are in substantial alignment with the sides 1 and 2 of the car, so that the whole forms a substantially funnel shaped car from which the load can be 60 evenly discharged.

The bell crank 31 is maintained in the 65 position it assumes when operated to release

the locking bolt by being forced against the side frame member 8 and frictionally held. This is accomplished by means of a coiled spring 43 which encircles the pivoting pin 44 of the bell crank and is held thereon between two washers 45 by a nut 46, see Figs. 4 and 5. The purpose of this is to retain the locking bolt in retracted position until the doors are again closed and locked and the car ready to receive another load.

70 The main advantages of this improved car reside principally in the great strength and simplicity of its structure, the construction of the dumping bottom and the improved locking and releasing mechanism for the 80 dumping bottom.

I claim—

1. In a car of the class described, a car body having a hinged bottom composed of two sections and means for locking said sections in closed position comprising a locking bar slidably mounted on one section and having a series of hooks and metal strips attached to the other section and having loops in which the hooks of the locking bar engage. 85

2. In a car of the class described, a car body having a hinged bottom composed of two sections and means for locking said sections in closed position including a locking bar and mechanism for retracting said locking bar consisting of a double crank operatively connected to the locking bar, and a bell crank operatively connected to the double crank. 95

3. In a car of the class described, a car body having a hinged bottom composed of two sections and means for locking said sections in closed position including a locking bar and mechanism for retracting said locking bar consisting of a double crank operatively connected to the locking bar, a bell crank, and a connection between the double crank and bell crank and universally jointed to each crank. 100

4. A car having a body provided with a hinged sectional bottom, mechanism for locking said sections together, and a system of universally connected cranks for retracting said locking mechanism. 110

5. A car having a body provided with a hinged sectional bottom, mechanism for locking said sections together, and a system of universally connected cranks for retracting said locking mechanism, one of which is supported from a stationary part of the car and another of which is supported from one of the hinged sections of the bottom. 115

6. In a car of the class described, a car body having a hinged bottom composed of two sections and means for locking said sections in closed position comprising a locking bar movably supported from one section and a plurality of elements attached at intervals to the other section having openings in which the locking bar engages. 125

7. In a car of the class described, a car body having a hinged bottom composed of two sections and means for locking said sections in closed position comprising a locking bar slidably mounted on one section and having a series of hooks and loops on the other section in which the hooks of the locking bar engage. 35
8. In a car of the class described, a car having a body and a hinged bottom composed of two sections hinged to opposite sides of the car body and adapted to be swung toward each other to close the opening in the car bottom and means for locking said sections in closed position including a locking bar supported from one member and adapted to operatively engage the other member; said locking bar having lugs and mechanism for retracting said locking bar 40 having a crank engaging the lugs of the locking bar. 45
9. In a car of the class described, a car body having a hinged bottom composed of two sections and means for locking said sections in closed position comprising a locking bar slidably mounted in longitudinal position on the side margin of one section of the bottom and having a series of hooks and a plurality of loops arranged at intervals on the side margin of the other section in which the hooks of the locking bar engage. 50
10. A car having a body provided with a dumping bottom, mechanism for locking the dumping bottom in closed position, and re- 55
- leasing mechanism for said locking mechanism including an element supported from the dumping bottom, an element supported from a stationary part of the car body and an extensible element connecting said elements. 60
11. A car having a body provided with a dumping bottom, mechanism for locking the dumping bottom in closed position, and re- 45
- leasing mechanism for said locking mechanism including an element supported from the dumping bottom, an element supported from a stationary part of the car body and an element connecting said elements; and consisting of a bar and two socket members each of which is fitted on one end of the base. 50
12. A car having a body provided with a dumping bottom, mechanism for locking the dumping bottom in closed position, and re- 55
- leasing mechanism for said locking mechanism including an element supported from the dumping bottom; an element supported from a stationary part of the car body and an element connecting said elements and 60 consisting of a screw threaded bar and two socket members, each of the socket members being screwed on one end of the bar. 65
